(57) **CLAIM**

The ornamental design for a cup shaped pod, as shown and described.

DESCRIPTION

FIG. 1 is a front perspective view of a cup shaped pod embodying the new design;

FIG. 2 is a top plan view thereof;

FIG. 3 is a rear side elevation view thereof; and,

FIG. 4 is a bottom plan view thereof.

The broken lines are included for the purpose of illustrating the portions of the cup shaped pod that form no part of the claimed design.
